UNITED STATES PATENT OFFICE.

HENRY STRAND, OF CLEVELAND, OHIO.

PORTABLE HONING OR LAPPING MACHINE.

Application filed December 10, 1924. Serial No. 754,977.

This invention relates to improvements in honing or lapping machines having for an object to provide portable means whereby the cylinders of an automobile engine may be expeditiously lapped without removal of the engine block from the chassis.

Another object is to provide a portable lapping machine adaptable to engine blocks having different numbers of cylinders and to include means for accurately centering the machine with respect to any particular cylinder.

A further object is to provide a portable lapping machine wherein a honing piston has a rotary and rectilinear movement in a cylinder.

It is likewise an object to provide a portable lapping machine including a frame attachable to a cylinder block and arranged to support a lapping tool so that it may be transversely and longitudinally shifted with respect to the engine block.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Figure 1 is a side elevation of the assembled lapping machine mounted upon an engine block;

Figure 2 is an end elevation of the machine shown in Figure 1;

Figure 3 is a slightly enlarged cross-sectional view taken on the line 3—3 of Figure 1;

Figure 4 is a plan view of the supporting frame, the legs being left out;

Figure 5 is a detail perspective view showing the structure of a clamp used in connection with this machine; and

Figure 6 is a detail sectional view taken on the line 6—6 of Figure 2.

Generally, in lapping or honing the cylinders of automobile engines it is necessary to move the block from the chassis and position it securely in a special frame. This operation obviously requires considerable labor and incidentally great expense to the owner, both being materially reduced through the use of a machine such as I shall describe in this application.

In my machine it is only necessary to remove the head of the engine and clamp the

lapping machine upon the block as clearly shown in Figures 1 and 2 of the accompanying drawings. After such positioning the usual or any preferred form of lap operating mechanism may be shifted longitudinally and transversely to accurately center the main shaft and lap over any particular cylinder. At this point the machine is started up and a compound rotary and rectilinear motion is transmitted to the lapping tool with the result that a cylinder may be accurately lapped.

Lap-operating mechanism.

This mechanism consists of a gear carrying frame 10 which as shown in Figure 3 is substantially triangular in cross-section having one side open and serving to house portions of the gears. Cast integral with this gear frame 10 at its open side is a pair of vertically aligned upper and lower shaft bearings 11 and 12 adapted to mount a drive shaft 13, to the lower end of which is removably attachable a lapping tool or piston 14, of any usual or preferred type.

Cast integrally with this gear frame or housing is a pair of vertically spaced upper and lower bearings 15 and 16 respectively in which are mounted stub shafts 17 and 18. The lower stub shaft 18 has fixed connection with a miter gear 19 which in turn meshes with a miter gear 20 carrying a sleeve 21 as shown in Figures 2 and 6. This sleeve 21 is of a length slightly greater than the lower shaft bearing 12 in which it is arranged and carries at its lower end a retaining ring or collar 22 which prevents accidental relative shifting as between said sleeve and bearing. The main drive shaft 13 is provided with a slot 23 adapted to receive a key 24 carried by the sleeve so as to permit rectilinear movement of the shaft simultaneously with rotary movement thereof. This rotary movement is obtained through the gear train within the gear frame or housing, this train comprising a relatively large spur gear 25 and a relatively small spur gear 26, the small gear being fixed to the inner end of the stub shaft 17 which is rotatable through a set of compound gears 27 from a motor 28 or the like. It is understood that this movement may be obtained through the use of a crank as well as a motor.

Rectilinear movement of the main shaft 13 is obtained through a slotted yoke crank motion which consists in the mounting of a

sleeve 29 upon the shaft 13 and securing it at a definite point through arranging lock or retaining rings 30 in contact with opposite ends of the sleeve. Integrally cast with 5 this sleeve 29 is a yoke 31 having a slot 32 formed longitudinally in its inner face for the reception of a slide block 33 which has a pintle 34 connected to a crank 35. This 10 crank 35 is pinned or otherwise fixed to the projecting end of the upper stub shaft 17 as shown in Figures 1 and 3. To provide against wobbling of the yoke 31 I removably secure at the opposite upper portions of the gear frame, retaining plates 36 which project inwardly toward one another sufficiently 15 to serve as guides for said yoke. These plates are rested upon sets of bosses 37 into which retaining bolts 38 are threaded.

With a structure as heretofore outlined 20 it is clear that with starting of the motor 28 motion will be transmitted to the gears 25 and 26 which in turn will effect the above stated rotary and rectilinear movement of the piston. As is apparent the rectilinear 25 movement is obtained through rotation of the crank 35 which carries the slide block 33 as indicated in Figures 2 and 3. This block moves longitudinally in the yoke 31 and effects a vertical movement of the yoke with 30 respect to the gear frame, thereby moving the sleeve 29 and shaft 13 vertically. The rotary motion is obtained through meshing of the miter gears 19 and 20, as is obvious. With the arrangement of the gears 25 and 26 35 as shown in Figure 2 the degree of rectilinear movement clearly exceeds the rotary movement and when it is desired to reverse the ratio, it may be readily accomplished through merely reversing the position of the 40 gears 25 and 26, the result being that there will be considerably greater rotary movement of the lapping piston with a proportionate lesser degree of the rectilinear movement. The arrangement of the upper and 45 lower shaft bearings 11 and 12 eliminates the usual slapping of the piston and insures accurate honing of a cylinder.

Supporting or carrying frame.

This frame is adapted to support the heretofore described operating mechanism directly upon an engine block and comprises a set of legs 39 whose lower ends are provided with enlarged foot portions 40 having pointed extremities 41 engageable with the vertical sides of an engine block E. The upper ends of the legs 39 are provided with enlarged head portions 42 having longitudinally aligned channels or ways 43 designed to 55 slidably mount main or base rails as shown in Figures 1 and 2. While any number of these legs might be employed in making up this supporting frame, I preferably use two, pairs of which are arranged transversely 60 aligned, each pair being inter-connected by 65

means of a lower transverse connecting rod 44 which is designed to draw the supporting legs together and tightly engage the pointed extremities 41 of the feet 40 with opposite portions of the engine block E. At times it 70 is necessary to move the legs outwardly and for this purpose I provide upper screw threaded rods or bolts 45 whose inner ends bear against the inner face of one of the legs 39 as shown in Figure 2. 75

Due to the difference in size of engine blocks it is necessary to vary the spacing of the legs 39 and in order to effect such spacing, the adjusting screws 44 and 45 are rotated to move these legs in substantially the 80 same manner as in the ordinary well known wood clamp used by cabinet makers.

In order to provide a connection between the piston operating mechanism and the supporting legs, such as will permit of longitudinal and transverse shifting of said mechanism, I provide a set of slide blocks and rails as shown in Figure 4. The main or base rails 46 extend longitudinally with respect to the engine block E and are each provided with slots 47 for the reception of machine bolts or screws 48 which are threaded into sockets formed in the ways or channels 43 of the supporting legs 39. A set of slide blocks 48' is provided and includes four substantially L-shaped blocks having relatively right angularly arranged ways or grooves in the upper and lower faces, the lower way 49 being adapted to straddle the upper portion of the base rail 46 while the upper way 100 or groove 50 slidably seats a pair of transverse supporting rails 5 as clearly shown in Figure 4. 95

These transverse supporting rails 51 are secured to the base flange 10' of the gear frame by means of machine screws or the like as shown in Figures 1, 2 and 3. It is obvious that with this structure the transverse bars and slides together with a lap operating mechanism may be shifted longitudinally upon the base rails 46 to a position over a cylinder, after which the transverse rails 51 with the operating mechanism may be moved transversely with respect to the slides 48' to accurately position the lapping piston for entry into a cylinder. 115

Obviously, after such shifting of the parts they must be locked in the final position, and in order to accomplish this I provide a pair of clamping devices which interlock the slides and several rails. Each clamping device comprises a top plate 52 which as shown in dotted lines in Figure 4 and in full lines in Figure 1, rests upon the end portions of the transverse rails 51 and is connected by means of a bolt 53 with a bottom clamp plate 54 whose structure is shown in Figure 5. This bottom plate 54 has a pair of fingers 56 which extend beneath and contact with the lower face of the main rail 120 125 130

46, the parts being so held through tightening of the bolt 53. A pair of studs 57 is carried by the lower plate 54 and extends upwardly into engagement with the slides 48' 5 to prevent improper relative positioning of the plates comprising the clamping device.

With a lapping machine constructed in accordance with the foregoing specification, it is possible to lap the cylinders of any 10 standard engine, the supporting legs and rails being relatively adjustable for fitting upon any sized cylinder block.

Manifestly, the construction shown is capable of considerable modification and such 15 modification as may fall within the scope of my claims, I consider within the spirit of my invention.

I claim:—

1. In a portable lapping machine, a vertical shell-like frame, substantially V-shape in transverse section to form one open side, vertically alined bearings at the open side of said frame, a shaft extending through said bearings, a cross-head fixed to the shaft, guides carried by the opposed walls of the open side to engage the cross-head, a crank pivoted at one end to the cross-head, a rotary shaft fixed to the other end of said crank, gearing arranged in the shell-like

frame to effect reciprocation of the cross-head and rotation of the shaft, and external drive gear having drive connection to the other gearing. 30

2. In a portable lapping machine, a shell-like frame open at one side, vertically alined bearings at the open side of the frame, an axially movable shaft journalled in said bearings, a yoke having a sleeve portion mounted on the shaft between said bearings, means connecting said sleeve portion of the yoke with the shaft so that the shaft can rotate in the sleeve and is held against axial movement independently of the yoke, said yoke having a cross head portion movable vertically in the open side of the frame, vertical guides for cross head, said cross head having a horizontal slot in its inner face, a block slideable in said slot, a pintle on said last named block, a horizontal rotary shaft supported in said frame, and a crank arm on said last named shaft having connection at its extremity with said pintle, whereby said yoke and said first named shaft will be reciprocated when said second named shaft is rotated. 35 40 45 50 55

In testimony whereof, I affix my signature.

HENRY STRAND.
